(57) **CLAIM**

The ornamental design for a flowerpot with integral soil anchor, as shown and described.

DESCRIPTION

FIG. 1 is a front top perspective view of a flowerpot with integral soil anchor, according to the present invention.

FIG. 2 is a front view thereof.

FIG. 3 is a back view thereof.

FIG. 4 is a left view thereof.

FIG. 5 is a right view thereof.

FIG. 6 is a top view thereof.

FIG. 7 is a bottom view thereof; and,

FIG. 8 is another perspective view thereof.

The broken lines in FIG. 6 are included to show a portion of the flowerpot with integral soil anchor that forms no part of the claimed design.

1 Claim, 7 Drawing Sheets(56)
